UNITED STATES PATENT OFFICE.

HENRY L. HASKELL, OF LUDINGTON, MICHIGAN, ASSIGNOR TO THE LUDINGTON NOVELTY COMPANY, OF SAME PLACE.

FOLDING TABLE.

SPECIFICATION forming part of Letters Patent No. 663,272, dated December 4, 1900.

Application filed December 30, 1899. Serial No. 742,102. (No model.)

To all whom it may concern:

Be it known that I, HENRY L. HASKELL, a citizen of the United States, residing at Ludington, in the county of Mason and State of Michigan, have invented certain new and useful Improvements in Folding Tables, of which the following is a full, clear, and exact specification.

My invention relates to that class of folding tables in which the legs are so arranged as to be folded flat against the under side thereof when not in use; and my invention has for its primary object to provide an improved and simple construction for holding the legs rigidly in their operative position and at the same time permitting them to be readily folded into a compact form and safe position against the under side of the table-top.

With these ends in view my invention consists in certain features of novelty in the construction, combination, and arrangement of parts by which the said object and certain other objects hereinafter described are attained, all as fully described with reference to the accompanying drawings, and more particularly pointed out in the claim.

In said drawings, Figure 1 is a vertical longitudinal section of my improved table, showing the legs in their operative position. Fig. 2 is a bottom plan thereof, showing the legs folded up; and Fig. 3 is a view similar to Fig. 1, also showing the legs folded up.

1 represents the table-top, which may be of the usual or any suitable construction, and to the under side of which are hinged a pair of cross-bars 2, each of which conjoins the legs at each end of the table in such way that both legs at each end may be simultaneously folded up against the bottom of the table-top and when in position, as in Fig. 1, will be rigidly braced. The pair of legs at one end of the table are so hinged and arranged with relation to the legs at the other end that when the two pairs of legs are folded up against the bottom of the table they will pass each other, as indicated in Fig. 2, thus permitting each pair to come against the table-top, and thereby not only make the folded form a compact one, but cause each pair of legs to project or guard the free ends of the other pair

and reduce to the minimum the liability of breakage.

Secured to the under side of the table-top 1 and extending longitudinally thereof is a bar 3, which, if desired, may be conveniently and cheaply constructed of wood and having its upper side adjacent to the table-top cut away, as shown at 4, to form a longitudinal slot, the upper side of the slot being constituted by the bottom of the table. This slot 4 forms a runway and guide for the upper end of each of two braces 5, whose outer or lower ends are pivotally attached to the legs at the opposite ends of the table. Each of these braces 5 is preferably V-shaped, as indicated in Fig. 2, having their diverged ends turned outwardly into sockets formed in the legs, as shown at 6, while at their upper ends they are formed with a transverse portion 7, which extends through the slot 4. When the legs are folded up, as in Figs. 2 and 3, the transverse portions 7 run along the slot to the mid-length thereof or approach each other, as will be understood, and when the legs are set up in their operative position they run to the outer ends of the slot, and if when in this position they are given a downward pull they engage in notches 8, extending downwardly from the bottom of the slot 4 and being formed on an incline extending inwardly, so that the braces may not be disengaged from such notches 8 during the ordinary use of the table, but in order to be disengaged for permitting the legs to be folded up must first be pulled outwardly and upwardly. When in operative position, however, the sides of the notches 8 are substantially at right angles to the end thrust of the braces 5, and consequently avoid accidental displacement of such braces.

Having thus described my invention, what I claim as new therein, and desire to secure by Letters Patent, is—

As a new and useful article of manufacture a folding table having a table-top, the legs hinged thereto, V-shaped braces pivotally secured to said legs for holding them in their operative position and a bar secured to the under side of the table-top and having its upper side adjacent to the top cut away from a point a short distance from each end toward

its mid-length so as to form with the table-top a longitudinal slot, said cut-away portion leading downwardly at its extreme outer ends to a notch 8 and said braces being passed 5 through said cut-away portion or slot and adapted to engage in said notches when the legs are in their operative position, the side of each of said notches remote from the brace

engaging therein being formed at an angle to such brace whereby the brace will abut there- 10 against and be locked thereby, substantially as set forth.

HENRY L. HASKELL.
